UNITED STATES PATENT OFFICE.

GEORGE E. NERNEY, OF ATTLEBORO, MASSACHUSETTS, ASSIGNOR TO BAY STATE OPTICAL COMPANY, OF ATTLEBORO, MASSACHUSETTS, A CORPORATION OF MAINE.

DESIGN FOR AN EYEGLASS FRAME.

Application filed November 18, 1926. Serial No. 19,758. Term of patent 14 years.

To all whom it may concern:

Be it known that I, GEORGE E. NERNEY, a citizen of the United States, residing at Attleboro, in the county of Bristol, State of Massachusetts, have invented a new, original, and ornamental Design for Eyeglass Frames, of which the following is a specification, reference being had to the accompanying drawing, forming part thereof.

In the accompanying drawing showing my new design, Figure 1 is a front elevation, Figure 2 is a top plan view and Figure 3 is a side elevation. The frame is of metal. The outer peripheral surfaces of the rims are formed by two flat gently sloping sur-

faces which at their intersection form what might be termed a ridge extending about the periphery of the rim. The top surface of the bridge is longitudinally grooved or concave and with the ridged surface of the rims it effects an assembly which is very pleasing in appearance. Because of the lines resulting from the contour described, the metal frame has the appearance of being thin and light when viewed from various angles.

I claim:

The ornamental design for an eyeglass frame as shown and described.

GEORGE E. NERNEY.
